UNITED STATES PATENT OFFICE

BURCHARD E. HORNE, OF ANDOVER, MASSACHUSETTS

ROOFING

Application filed June 24, 1928. Serial No. 118,156.

This invention relates to shingles, particularly those of the asbestos or composition type, and the method of applying them to a roof. It might be used with metal or wooden shingles if desired.

With one type of roof, rectangular shingles, with the lower and upper edges parallel to eaves and ridge, are used, the old method being either to mark a line along the lower edges or to use a straight edge. A type of roof to which my invention applies however is that in which the shingles are of rectangular or diamond shapes, with the points up, or of any shape in which the upper edges 10 are substantially in the form of an isosceles triangle, the upper points of all the shingles in any particular course being equi-distant 15 apart and in a line parallel with the ridge.

Great difficulty has been found in correctly 20 laying such shingles even where lines are drawn parallel with the ridge, or where a straight edge is used along the bottom edges or points. The bottom edges are often in 25 the shape of cut off points or may be all of more or less fanciful design.

I am well aware that notches and tangs and 30 other methods of marking the shingles in the various courses, to assist in properly alining them, have been used, but this particular invention applies to marks along the upper 35 edges of a shingle which is substantially pointed at the top, my markings being of such character that the lower mark of an upper course coincides with an upper opposite 40 mark of a lower course.

By this arrangement, if it is necessary to fasten down the bottom corner of the shingle, this may be done in any of various ways, but 45 the marks or marking slots along the upper edges are entirely covered up when the roof is finished, and do not show at all.

By the use of passages, by which term I also include notches, in my preferred construction if a roof is not even I can at any 50 stage of the laying, mark a straight parallel line on the roof and, as I can see this line through my notches or holes, I can at any time readily rectify the alinement.

When the lowest row of shingles is correctly 55 set, by using for at least part of my

setting marks, suitable passages such as notches or holes, I can cause the marks in the next course to accurately register on the opposite higher or lower marks on the two adjoining shingles in the lower course over the 55 edges of which it overlaps, and thus secure a perfect alinement.

I prefer to use notches, the lower edges of the two upper of which are in a line parallel with the edges of the lower notches, both 60 lines to be parallel with the ridge.

The type of shingle to which my invention applies has at the top two horizontal adjacent substantially straight edges which come together at a junction, which is intended to be laid at the top. The other two edges are preferably substantially straight and come together in such form that when laid, they 65 cover the right and left junction points of the next lower course, and also the upper 70 junction of the second lower course.

In referring to the edges of the shingles I will described the two adjoining top edges as the top edges, and the other two as the bottom edges, and will refer to the upper left and lower right marks as opposites, and the upper right and lower left marks as opposites.

In the drawings, Fig. 1 is a view which may be called a plan or elevation as it shows a 80 roof, the pitch of which is usually about 45°, covered with one type of shingles embodying my invention, part of the roof being broken away to show a working line for the roof.

Fig. 2 is a view similar to Fig. 1 of a section of roof on a somewhat larger scale, certain parts being indicated by dotted lines, and others broken away for clearness.

Fig. 3 shows a single shingle of the type 90 shown as laid in Figs. 1 and 2.

Figs. 4, 5 and 6 show other types of shingles with my device applied thereto.

Fig. 7 is a view similar to Fig. 2 but on a still larger scale, and with various sections 95 broken away to show the construction.

Fig. 8 shows the application to another slightly different type of shingle.

Fig. 9 shows a different kind of alining mark or hole.

Fig. 10 shows an alternative construction. 100

Fig. 11 shows a single shingle and Fig. 12 a roof of a modified type.

Fig. 13 shows another modification.

In the drawings, A represents a roof which is shown as of rectangular shape, with the ends 3 and 4, bottom edge 2 and ridge 1.

B represents generally shingles of the type indicated, while B¹, B², B³, B⁴, shows how these shingles are laid.

Each shingle is of substantially rectangular or diamond shape, the bottom edges 11 and 14 instead of coming to a point, being cut off at 10.

The top edges 12 and 13, instead of coming to a point with the bottom edges 11 and 14, are formed into the tangs 16 and 17 while near the bottom the material is cut at 115 to form a locking tang 15, which as shown in Fig. 7, is intended to pass under 16 and 17, thus holding down the bottom part of the shingle.

The top point between the sides 12 and 13 is also cut away at 18, but this is merely a result of the method of cutting the tang 17 from the stock.

The top edges 12 and 13 of each shingle have two sets of oppositely disposed notches or marks 20 and 21, and 22 and 23, which are preferably of angular form, the lower edges, such as 120 and 123, of each notch, being parallel with the ridge when the shingles are laid. Such lower edges in all cases are of the same length, while the upper edges such as 220 and 223 are of equal length. When such notches are superimposed as shown in Fig. 7, they form a triangular passage through which a line, such as X—Y, marked on the roof can be seen.

Such a line X, Y, is also shown in Fig. 1 and Fig. 2, and it is obvious that where a locking tang such as 15 or any other locking device such for instance as L, shown in Fig. 8, is used, the bottom point or junction of the bottom edges can be located and held while the two oppositely disposed bottom notches such as 22 and 23 are lined up on a line such as X, Y, or are lined up with the top edges such as 12 and 13 of the shingles of the next lower course whether such shingles have any top notches such as 20 and 21 or not. Moreover as the lowest course is accurately started, it is clear that if only the bottom notches or marks on the top edges are used in connection with any third point such as tang 15, the shingles of an upper course can individually be accurately positioned with reference to those on the next lower course and the roof in general. On the other hand if there is no fastening device at the lower point, see Figs. 9 to 13, either or both of the upper marks make the third positioning means or indicator whereby each shingle can be accurately placed.

However if there is no locking means for the bottom point and no top marks, but only the two marks, one near the bottom end of

each top edge, they are of great practical assistance in accurately placing each succeeding upper course by using a chalk line such as X, Y, or merely by sighting along them with the eye and getting them in a straight line parallel with the bottom edge of the roof.

Referring to Fig. 7, the lowest course, the shingles of which may be indicated by B¹, can be laid along the bottom edge 2 of the roof, or along a marked line or straight edge, making the part 10 parallel with the ridge and the diagonal line from 18 to 10 at right angles thereto.

A shingle of the next course such as B², is so laid that the lower edge 123 of the bottom right notch of its upper edge 13 coincides with and lies directly over the bottom edge 120 of the upper left notch in the opposite upper edge 12 of the next lower course B¹. This brings the tang 17 in position where, when the next shingle B⁴ at the right is similarly laid, the tangs 16 and 17 abut against each other and the locking tongue 15 of the shingle B³ in the next higher course 90 can pass under 17 and 16, thus holding down the bottom edge of B³, in a well known manner.

In every case, the lower notch on one side is made to lie over or coincide with the upper notch on the opposite side of the shingle in the course below, making the notches register.

My device may be applied to shingles such as shown in Fig. 4 at F, which have their own peculiar locking device 56 at the bottom, by cutting the two sets of oppositely disposed notches 50 and 51, 52 and 53 in the upper edges thereof.

In Fig. 5, at G, another type of bottom fastening device 66 is shown together with setting notches 60, 61, and 62, 63.

In Fig. 6 the shingle C has no locking device at the bottom although it may be turned up underneath as indicated at 35 if desired, and this has the setting notches 30, 31 and 32, 33.

This type of shingle as shown in Fig. 8, may be used in connection with a fastener of metal L which holds down the bottom edge.

As shown in Fig. 9, I may use as marking 118 passages, the holes 320, 321, 322, 323, pierced through and proximate the top adjoining edges 318, 319.

In this case, I cause the lower right hole 323 of an upper course shingle K² to register with the upper left hole 320 of a lower course shingle K³, and cause the lower left hole 322 to register with an upper right such as 321 of a lower course.

The essential feature of my invention is the use of two sets each of two marks, preferably in form of passages placed near the top edges; the two upper marks being at equal distances from the top and the two 130

lower marks being at equal distances therefrom.

I may use as shown in Fig. 11, passages or holes such as 72 or 73 for the lower marks, 5 and merely dots or other similar marks such as 70 and 71 for the upper marks.

In this case the holes 73 and 72 of the course indicated by M^2 and M^4 are passed over the upper marks 70 and 71 of the lower 10 course shingle M^3 , care being taken to center them like the bull's-eye of a target. When the courses indicated by M^3 and M^2 and M^4 are laid, the lower ends of the next course M^1 cover up the marks entirely as shown in 15 Fig. 12.

As shown in Fig. 13, instead of any passages, I may use marks such as painted lines, or creases, or rows of punctures.

These are shown on the shingles P^1 , P^2 , P^3 , 20 P^4 . Two upper marks are indicated by 80 and 81 and the two lower marks by 82 and 83.

As shown, these are of angular form, but it is obvious that various other forms might 25 be used.

The end of each upper mark 81 on a shingle such as P^1 in a lower course registers with the end of a lower mark such as 82 on the top adjoining edge of a shingle such 30 as P^3 in the next upper course.

The end of mark 83 on shingle P^2 registers with the end of mark 80 on shingle P^3 .

I claim:

1. The combination with a pitched roof 35 having a substantially straight horizontal ridge; of a plurality of shingles each of substantially rectangular shape positioned with a point towards the top and in overlapping courses from the bottom toward the top, the 40 bottom edges of the upper rows over-lapping the top edges of the next lower row; the top edges of each shingle having two sets of similar oppositely disposed angular notches the lower edge of each notch being parallel with 45 the ridge, the lower edges of the upper notches being in the same line and the lower edges of the lower notches being in a different line, both lines being parallel with each other and with the ridge, the lower notch on one side 50 of each shingle being over and registering with the upper opposite notch of a shingle in a lower course.

2. A roof comprising a plurality of horizontal courses of shingles arranged so that 55 the shingles of successive courses partly overlap the shingles of the next lower course, each of said shingles having its upper part formed as an isosceles triangle each side of which 60 has two angular notches, the lower edges of the two upper notches being in line and the lower edges of the two lower notches being in line, such lines being parallel with the courses of shingles and the lower edge of 65 each lower notch of an upper course register-

ing with the lower edge of an upper opposite notch of a shingle in a lower course.

3. A roof comprising a plurality of horizontal courses of flat flexible fiber shingles arranged so that the shingles of successive courses partly overlap the shingles of the next lower course, each of said shingles having its top edges disposed at an angle with the courses of shingles and each top edge having an upper passage, such upper passages 70 being in a line parallel with the courses and each top edge having a lower passage, such lower passages being in a line parallel with the courses, the lower passage of an upper course registering with the upper opposite 75 passage of a lower course.

4. A roof comprising a plurality of horizontal courses of flat flexible fiber shingles arranged so that the shingles of successive courses partly overlap the shingles of the 80 next lower course, each of said shingles having its top edges disposed at an angle with the courses of shingles and each edge having proximate its upper end an upper mark and near its lower end a lower mark; the upper 85 mark on one edge of a shingle in a lower course registering with the lower opposite mark of a shingle in the next upper course.

5. A roof comprising a plurality of horizontal courses of flat flexible fiber shingles 90 arranged so that the shingles of successive courses partly overlap the shingles of the next lower course, each of said shingles having its top edges disposed at an angle with the courses of shingles, and each top edge 95 having near its upper end an upper mark, and near its lower end a lower mark, the upper marks being equidistant from the top and the lower marks being equidistant from the top, the upper mark on one edge of a 100 shingle in a lower course registering with the lower opposite mark of a shingle in the next 105 upper course.
